US00D632575S

(12) **United States Design Patent**
Walker

(10) **Patent No.:** **US D632,575 S**
(45) **Date of Patent:** **** Feb. 15, 2011**

(54) **COLLAPSIBLE CONTAINER**

(76) Inventor: **Allison Janet Walker**, 2109 Azalea Cir., Decatur, GA (US) 30033

(**) Term: **14 Years**

(21) Appl. No.: **29/352,449**

(22) Filed: **Dec. 21, 2009**

Related U.S. Application Data

(63) Continuation of application No. 29/317,063, filed on Apr. 22, 2008, now Pat. No. Des. 606,416.

(51) **LOC (9) Cl.** **09-01**

(52) **U.S. Cl.** **D9/516**

(58) **Field of Classification Search** D9/516, D9/529, 537, 539, 540, 548, 549, 550, 551, D9/552, 558, 563, 564, 571, 574, 683; 215/381-385, 215/379, 900; 220/600, 608, 609, 660, 669, 220/670, 675, 907; D7/601, 619.1, 619.2, D7/622, 624.2, 624.3

See application file for complete search history.

(57) **CLAIM**

The ornamental design for a collapsible container, as shown and described.

DESCRIPTION

FIG. 1 is a perspective view of a collapsible container showing my design;

FIG. 2 is a left side view thereof;

FIG. 3 is a front view thereof;

FIG. 4 is a right side view thereof;

FIG. 5 is a back view thereof;

FIG. 6 is a bottom view thereof; and,

FIG. 7 is a top view thereof.

The portions of the collapsible container shown in broken lines are for illustrative purposes only and form no part of the claimed design.
